(57) **CLAIM**

The ornamental design for an electric food processor, as shown and described.

DESCRIPTION

FIG. 1 is a front elevational view of an electric food processor showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a perspective view thereof.

The broken lines in the drawings and the areas within depict portions of the electric food processor that form no part of the claimed design.
